(57) **CLAIM**

I claim the ornamental design for a cable protector, as shown and described.

DESCRIPTION

FIG. 1 is a perspective view of a cable protector in use condition, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is an exploded front perspective view thereof;

FIG. 9 is an exploded front elevational view thereof;

FIG. 10 is an exploded right-side elevational view thereof;

FIG. 11 is an exploded left-side elevational view thereof;

and,

FIG. 12 is an exploded top plan view thereof.

The broken line in FIG. 1 drawing view represents unclaimed environment only and forms no part of the claimed design.
